PITTSBURGH STEEL COMPANY, OF PITTSBURGH, PENNSYLVANIA, A CORPORATION
OF PENNSYLVANIA.

SAFETY DEVICE FOR WIRE-DRAWING APPARATUS.

1,296,221.

Specification of Letters Patent.

Patented Mar. 4, 1919.

Application filed January 30, 1918. Serial No. 214,510.

To all whom it may concern:

Be it known that we, GEORGE O. ROSE and THOMAS KURTZ, citizens of the United States, and residents of Monessen, in the 5 county of Westmoreland and State of Pennsylvania, have invented new and useful Improvements in Safety Devices for Wire-Drawing Apparatus; and we do hereby declare the following to be a full, clear, and 10 exact description thereof.

Our invention relates to a safety device for wire-drawing apparatus.

In the drawing of wire, the wire is unwound from a freely-rotating reel and is 15 drawn through the drawing-die by a power-driven drum. The operator has to stand adjacent to the drum and die for feeding the die with lubricant and for stopping the rotation of the drum when necessary; and 20 during the drawing of the wire, it sometimes happens that the operator comes in contact with the wire, and in many instances has become entangled in loops and kinks of the wire between the die and the reel and 25 suffered injury and even lost his life by being drawn with the wire into contact with the machine. A loop or kink in the wire will also very often cause the wire to break if the loop or kink is drawn against the die, 30 this breaking of the wire resulting in considerable loss by reason of time required for replacing a new bundle, as the broken bundle must be taken off of the winding drum and a simple and efficient form of new one 35 started.

The object of our invention is to provide a safety device which will act automatically to shut off the winding of the wire on the drum and so avoid the serious accidents and 40 delay which have heretofore happened in this class of apparatus.

To these ends our invention comprises the novel features hereinafter set forth and claimed.

45 In the accompanying drawing, Figure 1 is a plan view of wire-drawing apparatus with our safety device applied thereto; Fig. 2 is an end view; Fig. 3 is a view taken at right angles to Fig. 2; Fig. 4 is a vertical section of the winding-drum and means by which it is connected to the vertical shaft; and Figs. 5 and 6 are details.

In the drawing, the numeral 2 designates a suitable draw-bench or frame in which the

shaft 3 is journaled, which is connected up 55 to any suitable source of power. Mounted on the shaft 3 is the bevel-gear 4, which meshes with the bevel-gear 5 on the vertical shaft 6, which is arranged in suitable bearings in the draw-bench 2. Loosely mounted 60 on the upper end of the vertical shaft 6 is the winding-drum 7 of ordinary construction, said winding-drum having the detents 8 depending therefrom, said detents being adapted to engage the ratchet member or 65 plate 9 rigidly secured to the vertical shaft 6. It will be apparent that when the detents 8 are in engagement with the ratchet-plate 9, as indicated in Fig. 4, that a rotary motion will be imparted to the drum 7. 70

A guard-lever 10 is pivoted at 11 to a plate 34, which is secured to the angle-bar 12 of the frame 2, the lower end of said lever being connected by a clevis 13 and the link 13' to the guard-lever 14. This lever 75 has the upwardly-extending portion 15 with the loop 16 through which the wire 17 passes on its way from the reel (not shown) to the die 18 mounted on the draw-bench 2.

The plate 34 supports a latch 20 which 80 carries the weighted arm 21, being connected thereto at 22, and having the link-connection 23. The outer end of the arm 21 has the weight 26 suspended therefrom. A cable 27 connected to the outer end of said 85 arm and passing over a pulley 28 to the front of the draw-bench is provided for returning the parts to normal position as will hereinafter be described.

The latch 20 is made up of two parts 29 90 and 30, and is assembled on the plate 34 with the plate between these parts. The parts are connected by the bolts 31, the lower bolt forming the point of connection of the arm 21 to said latch, and the upper 95 bolt forms a journal for the roller 32, which is between the latch parts and is adapted to engage and rest on a shoulder or offset 33 in the plate or keeper 34, which is secured to the angle-iron 12.

A link 35 is pivotally connected to the angle-iron 12, and to the link 23, and forms the fulcrum upon which the weighted arm 21 swings when said arm is released.

To prevent disengagement of the latch 20 105 from its seat through vibration, links 36-37 connecting the guard-lever 10 and the plate 34 are provided. These links when the parts

are in normal position confine the latch against movement, link 37 engaging the laterally-extending portion of the latch, and is moved only when the operating guard-lever 10 is moved. Links 36, 37 are also for the purpose of pushing the roller 32 of latch 20 into the slot or offset 33 of the plate 34, when said latch 20 is raised again to normal position.

10 The upper end of the latch 20 has a lateral extension or head 20' which extends over the outer end of the lever-arm 39, which projects through the opening 34' of the plate 34. This arm 39 is connected to the 15 yoke 40, which is pivotally mounted, as at 41, to the frame of the draw-bench 2. The yoke 40 carries the shoes 42, which are adapted to engage the lower face of the drum 7 when the yoke is rocked on its 20 pivots to raise the drum out of engagement with its driving element. In normal position of the lever-arm 39, as indicated by the full lines, Fig. 3, the drum 7 is in its lowered position, with the detents engaging the 25 ratchet-plate 9, and the drum 7 is rotated by the shaft 6.

In the operation of the device, under normal conditions, the wire 17 coming from the supply-reel passes through the loop 16 of the guard-arm 14, through the die 18, and around the drum 7. The drum 7 is rotated by the connections heretofore described, and as long as the wire is fed evenly to the die, the reeling of the wire on the drum 7 takes place without incident. If, however, the wire by reason of a kink or loop, or for other cause, should in any way catch or gather around the operator so as to be drawn or moved by the wire against the guard-arm 14, said guard-arm would be moved into the position indicated by dotted lines, Fig. 1, and in its movement will act through the connections described to throw the guard-lever 10 to the position indicated in dotted lines, Fig. 2, said movement of the lever will act through the connections described to throw the latch 20 out of engagement with its seat or shoulder 33, whereupon said latch will drop into the position indicated in dotted lines, Fig. 2, due to the weighted arm 21 and its connection with said latch. The lowering of the latch 20 with its head 20' in engagement with the outer end of the lever-arm 39 will through the connections described rock the yoke on its pivots and raise the drum 7 and disengage the detents 8 from the ratchet-plate 9, thus stopping the rotation of the drum. In this manner, the guard-arm 14 by the thrust of the body of the operator against it will automatically act to stop the rotation of the drum 7, and what might have resulted in a very serious or even fatal accident to the operator is rendered harmless, and the further winding of the wire is stopped until the operator can

disengage himself from the entangling wire. The same actuation of parts to stop the drawing drum will occur if in some manner the operator should get his hand entangled in the wire on the other side of the die and be drawn toward the drum, as it will readily be seen the operator would be drawn into contact with the lever 10, which would trip the holding latch 20, or be drawn to such position that he could operate the lever to stop the machine. It is apparent also that the operator can at any time control the rotation of the drum 7 by moving the guard-lever 10 by hand, which through the connections described will act to lower the latch 75 and throw the drum out of rotative engagement with the shaft 6.

It has been customary heretofore to operate the clutch mechanism solely by a treadle, and as it is more convenient under ordinary 85 circumstances to employ such treadle so that both hands of the operator will be free, we have illustrated the connection to such treadle by the numeral 45.

When it is desired to bring the parts back to position again for reeling, the cable 27 is drawn up and the arm 21 raised to its normal position, which will act to bring all parts back to their normal position with the latch 20 engaging its keeper, and as said latch is raised the weight of the drum 7 will act to restore the lever-arm 39 to its normal position and will bring the detents 8 into position for engagement with the ratchet-plate 9.

What we claim is:

1. In a safety device for wire-drawing apparatus, the combination of a suitable frame, of a drum, a power-driven shaft, clutch connections between said shaft and said drum, a locking device for holding said drum in engagement with said shaft, a weight-controlled arm, connections between said locking device and said weight-controlled arm, a movable guard-arm, and connections between said arm and said locking mechanism whereby by the movement of said guard-arm said locking mechanism is released and said weighted arm moves the drum out of engagement with said shaft.

2. In a safety device for wire-drawing apparatus, the combination with a suitable frame, of a drum, a power-driven shaft, clutch connections between said shaft and said drum, a latch, a keeper engaged by said latch, a weighted arm, connections between said arm and said latch, a movable guard-arm, and connections between said guard-arm and said latch whereby by the movement of said guard-arm said latch is released from said keeper; and by the action of said weighted arm said drum is disengaged from said shaft.

3. In a safety device for wire-drawing apparatus, the combination with a suitable

frame, of a drum, a power-driven shaft, clutch connections between said drum and said shaft, a latch, a keeper for said latch having an offset on which said latch is supported, a weighted arm connected to said latch, a movable guard-arm, and connections between said latch and said guard-arm whereby when said guard-arm is moved said latch is released from its support and said 10 drum is lifted from engagement with said shaft by the action of said weighted arm.

4. In a safety device for wire-drawing apparatus, the combination with a suitable frame, a drum, a power-driven shaft, clutch 15 connections between said shaft and said drum, a lever-arm for actuating said clutch mechanism, a latch, a projection on said

latch overhanging said lever-arm, a weighted arm connected to said latch, a movable guard-arm, and connections between said 20 latch and said guard-arms whereby by the movement of said guard-arm said latch is released and lowered by the action of said weighted arm to operate said lever-arm to release said drum from said power-shaft. 25

In testimony whereof, we the said **GEORGE O. ROSE**, and **THOMAS KURTZ**, have hereunto set our hands.

GEORGE O. ROSE.
THOMAS KURTZ.
